(57) **CLAIM**

The ornamental design for a holder for a drill alignment device, as shown and described.

DESCRIPTION

FIG. 1 is a top front perspective view of a holder for a drill alignment device, showing our new design;

FIG. 2 is a top front perspective view in an exploded state;

FIG. 3 is a front side elevation view thereof;

FIG. 4 is a rear side elevation view thereof;

FIG. 5 is a left side elevation view thereof;

FIG. 6 is a right side elevation view thereof;

FIG. 7 is a top side plan view thereof; and,

FIG. 8 is a bottom side plan view thereof.

The broken lines shown in the drawings represent unclaimed portions of the holder for a drill alignment device and form no part of the claimed design.
